UNITED STATES PATENT OFFICE.

FRANK ANSLEY, OF SPOKANE, WASHINGTON.

SPINNING-TOP.

SPECIFICATION forming part of Letters Patent No. 758,291, dated April 26, 1904.

Application filed August 24, 1903. Serial No. 170,547. (No model.)

To all whom it may concern:

Be it known that I, FRANK ANSLEY, a citizen of the United States, residing at Spokane, in the county of Spokane and State of Washington, have invented certain new and useful Improvements in Spinning-Tops; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to new and useful improvements in spinning-tops, and especially in the provision of a wheel having a series of blades about its circumference positioned at angles to the face of the wheel, said wheel having a shaft one end of which is recessed and adapted to receive the point of a pivotal pin, thereby reducing the friction to a minimum and affording a means whereby when a blast of air is directed through the nozzle against the blades a rapid movement may be imparted to the wheel.

The invention consists, further, in various constructions, combinations, and arrangements of parts, which will be hereinafter fully described and then defined in the appended claim.

My invention is illustrated in the accompanying drawings, which, with the letters of reference marked thereon, form a part of this application, and in which drawings similar letters of reference indicate like parts in the views, in which—

Figure 1 is a perspective view of my improved top, and Fig. 2 is a longitudinal sectional view through the frame supporting the shaft and showing the shape of the blades on the rotary wheel.

Reference now being had to the details of the drawings by letter, A designates the base portion of a frame having a yoke B, which may be of any desired shape, and in the drawings is shown in rectangular outline, and rising from the base adjacent to its center is a pivot-pin D, and E designates a shaft, the lower end of which is recessed and adapted to receive said pivot-pin, while the other end of the shaft is pointed and has a bearing in an aperture or indentation in the horizontally-

disposed portion of said yoke. H designates a wheel which is fixed to said shaft and has a series of blades H' about its circumference which are bent at angles to the face of the wheel and preferably of the shape shown in Fig. 2 of the drawings, in which positions they are adapted to receive the impact of the blast of air directed against the same through a tube or nozzle K. Said nozzle K is mounted in a socket N, mounted upon one of the upright portions of said yoke, and is so positioned with relation to the circumference of said wheel that the full force of the blast of air directed through the nozzle will impinge against the blades and cause a rapid rotary movement to be imparted to the wheel.

While I have shown the top as mounted upon a pin carried by a framework, it is my purpose to spin the top upon the point of a pin or needle without any reference to the frame whatever.

While I have shown a particular construction of top embodying the features of my invention, it will be understood that I may make alterations in the detailed construction of the same, if desired, without departing from the spirit of the invention.

Having thus fully described my invention, what I claim as new, and desire to secure by Letters Patent, is—

A spinning-top comprising a base, a rectangular-outlined frame having angled ends fastened to the upper surface of said base, a pintle rising centrally from the base and intermediate the ends of said frame, a shaft having a winged wheel rotating therewith, one end of said shaft having a bearing upon said pintle at a slight distance above said base, the upper end of the shaft tapering and having a bearing in an indenture in the upper horizontally-disposed portion of the frame, an eye having a shank portion secured to the upright portion of said frame and a nozzle mounted in said eye at one edge of the frame, and outside the latter and held at an inclination to said wheel, as set forth.

In testimony whereof I hereunto affix my signature in presence of two witnesses.

FRANK ANSLEY.
